(57) **CLAIM**

The ornamental design for a dinner plate as shown and described.

DESCRIPTION

FIG. 1 is a front and top perspective view of a dinner plate showing my new design;

FIG. 2 is a front and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view thereof shown in an exemplary environment; the dash-dot-dot broken lines shown in FIG. 9 depict an environmental article that form no part of the claimed design.

The even spaced broken lines shown in the drawings depict portions of the article that form no part of the claimed design.

The blank regions from no part of the claimed design.
